DESIGN FOR A SUIT

Toni Carnegie, New York, N. Y.

Application June 27, 1941, Serial No. 101,726

Term of patent 3½ years

To all whom it may concern:

Be it known that I, Toni Carnegie, a citizen of the United States, residing in New York city, in the county of New York and State of New York, have invented a new, original, and ornamental Design for a Suit, of which the following is a specification, reference being had to the accompanying drawing, forming part thereof.

I claim:

The ornamental design for a suit, substantially as shown.

TONI CARNEGIE.
